BRACELET

Herbert H. McFarland, San Francisco, Calif.

Application November 23, 1947, Serial No. 142,856

Term of patent 3½ years

(Cl. D45—4)

To all whom it may concern:

Be it known that I, Herbert H. McFarland, a citizen of the United States of America, residing at San Francisco, in the county of San Francisco and State of California, have invented a new, original, and ornamental Design for a Bracelet, of which the following is a specification, reference being had to the accompanying drawing, forming a part thereof.

Fig. 1 is a developed plan view of the top of a bracelet, showing my new design,

Fig. 2 is a side elevational view of the bracelet as shown in Fig. 1,

Fig. 3 is a longitudinal section throughout the center of the bracelet as shown in Fig. 1,

Fig. 4 is a developed plan view of the bottom of the bracelet, and

Fig. 5 is a perspective view thereof.

I claim:

The ornamental design for a bracelet, substantially as shown.

HERBERT H. McFARLAND.
